BANK

Filed Feb. 10, 1922

Fig. 5.

INVENTOR
Paul A. Holmes.
BY *Arthur L. Brown*

ATTORNEY

UNITED STATES PATENT OFFICE.

PAUL A. HOLMES, OF KANSAS CITY, MISSOURI.

BANK.

Application filed February 10, 1922. Serial No. 535,621.

To all whom it may concern:

Be it known that I, PAUL A. HOLMES, a citizen of the United States, residing at Kansas City, in the county of Jackson and

5 State of Missouri, have invented certain new and useful Improvements in Banks; and I do declare the following to be a full, clear, and exact description of the invention, such as will enable others skilled in the art 10 to which it appertains to make and use the same, reference being had to the accompanying drawings, and to the figures of reference marked thereon, which form a part of this specification.

15 This invention relates to banks and particularly to a bank in which certain mechanism will operate upon the insertion of a coin through the coin opening in the bank casing or housing.

20 The primary object of the invention is to provide a bank in which the act of introducing a coin into the bank will cause certain mechanism to operate in a predetermined manner and whereby the amount

25 deposited in the bank can be registered on indicating wheels if the coins are introduced in a certain way.

30 Means are also provided whereby certain units of savings can be registered in the bank and the accumulation of multiples of the units or fractions thereof will be indicated on certain indicating wheels, visible through windows in the casing. For example, the bank is particularly applicable for use as a preliminary depository for moneys to be placed in savings banks, the invention being a home bank which will receive the initial deposits. The object is to accumulate a given amount, in the present instance 35 \$5.55, this being the unitary amount. If a second unitary amount say \$11.10, is deposited in the bank in the manner for which the bank is designed, the indicating wheels will register this second accumulation and

40 any fraction can also be registered.

45 The invention resides particularly in the novel construction of the bank, which will be clearly understood by reference to the following description in connection with the accompanying drawings, in which—

50 Fig. 1 is a perspective view of a bank constructed in accordance with my invention, part of one side wall being broken

away to show the means for supporting the registering wheel housing. 55

Fig. 2 is a vertical, transverse, sectional view through the bank.

Fig. 3 is a detail perspective view of the registering wheel mechanism and the case in which it is mounted. 60

Fig. 4 is a fragmentary perspective view of part of the case, showing the pawl supporting spring and the fulcrum therefor, and

Fig. 5 is a detail perspective view of one 65 of the pawl supporting springs and the pawl attached thereto.

The housing 1 of the bank consists of an enclosing casing having a bottom opening 2, adapted to be closed by the bottom of the 70 registering mechanism case and by a lock plate to be described hereinafter. The housing has an inclined face 3, in which are coin slots 4, 5, 6 and 7 and in the side walls of the housing are openings 8 through which 75 paper money may be introduced.

Below the coin slots are windows or sight openings 9, 10 and 11, opposite which the perimeters of certain registering wheels may be positioned. 80

In the sides of the housing 1 are guide ribs 12, extending transversely of the housing and preferably pressed out from the side walls. These constitute guide and supporting ribs for the side walls 13 and 14 85 of a registering mechanism case. The registering mechanism case consists, besides the side walls 13 and 14, of a bottom 15 and a rear wall 16. The side walls 13 and 14 have grooved portions 13' and 14', constituting 90 guides for the ribs 12, which may enter them into engagement in the slots 17 and 18 in the side walls 13 and 14 so that the case will be held against vertical movement with respect to the housing 1. 95

Mounted in the side walls of the registering mechanism case is a rigid shaft 19, on which are rotatable registering wheels 20, 21 and 22, spaced apart by spacing sleeves 23 on the shaft 19 and between the 100 respective wheels. Each wheel carries a ratchet 24, the ratchets being adapted to be engaged against backward movement by the spring pawls 25, 26 and 27 on the pawl-carrying bar 28 fastened to the side walls 105 13 and 14 of the mechanism case.

2

Mounted in the upper portions of the side walls 13 and 14 is a wheel-actuating mechanism supporting bar 29, to which are secured the upward and rearwardly extending spring strips 30, 31 and 32, each bearing against a cut-out portion 33 in the rear wall 16 so that the cut-out portion 33 for each member 30, 31 and 32 constitutes a fulcrum. The free upper end of each strip 30, 31 and 32 carries a hanging movement-imparting pawl 34, which is bodily movable in an arc when the upper end of its strip 30, 31 or 32 as the case may be, is sprung rearwardly. When it moves downward, it will engage one of the teeth of one of the ratchets 24 to impart a rotating movement thereto and the ratchet, in turn, will impart a rotating movement to its particular wheel or disk. The upper ends of each spring strip 30, 31 and 32 are in line with and in rear of the openings 4, 5 and 7; there being no ratchet mechanism to be operated when a coin is introduced into the slot 6. The slot 4 is designed to receive dimes or ten cent pieces and the disk or wheel 20 is divided into ten spaces from 00 to 90 to provide for the ten decimal fractions of a dollar. The perimeter of the disk 21 is divided into two sets of spaces having numbers 1 to 5 thereon, and each set is spaced from the other at each end by a blank space. The numbers 1 to 5 have exponent numbers or small numbers at their upper edges, increasing by the value of five. For example, in the "1" space there is a small number 05; in the "2" space appears a small number 10; in the third space is a small number 15; in the fourth space a small number 20, and in the fifth space a small number 25. Then there is a blank space and the second half of the disk is again spaced 1, 2, 3, 4 and 5 with the progressively increasing small numbers 05, 10, 15, 20 and 25, as above described.

On the disk 22 the spaces are divided into any number of subdivisions as, for example, One to Ten, and beneath each main number One to Ten, is a small number 5.55; this being the unit of saving for which the bank is designed.

The owner of the bank is supposed to introduce dimes in the opening 4 until ten have been deposited. Then 00 will appear opposite the window 9. Upon the insertion of a nickel in the slot 5, the wheel 21 will be thrown over one space so that through the window 10 the number 1 with 05 in small figures at the upper right hand corner will appear, showing that 1.05 has been deposited.

When the operator puts in ten more dimes in the slot 4, 00 will again register and another nickel is to be deposited in the slot 5,

when 2 with the small figures 10 appearing at the right hand corner will appear in the space, it being understood that each time a coin is forced into a slot, except in slot 6, a disk will be thrown over one space. 70

If ten more dimes are inserted in the slot 4, 00 will again appear. Then a nickel is to be placed in the slot 5 when 3¹⁵ will be observed through the window 10. It is understood, of course, that the ten dimes need not all be put in the bank at one time but dimes only should be placed in the slot 4 and nickels in the slot 5; the nickels being necessary to throw over the dollar wheel, the wheel 20 being the dime wheel. 80

The operation just described is continued until 5²⁵ appears opposite the window 10; then the operator inserts another nickel in the slot 5, throwing over the wheel 21 to present the blank space opposite the window 10 and then a quarter is inserted in the slot 7, which throws over the wheel 22 one space, making the word "One" appear opposite the window 11, but beneath the word "One" will appear in small figures 5.55, which will indicate that \$5.55 has been deposited in the bank; that is, five dollars in dimes, the five nickels for the five divisions of the wheel 21, and another nickel to throw the wheel over to present the blank space and the quarter which has been inserted in the space 7, making \$5.55. Then 00 will appear opposite the window 9, a blank opposite window 10 and "One" with 5.55 below it opposite window 11, so the bank will indicate that \$5.55 has been deposited. 90

Then the operation begins over until another \$5.55 has been deposited, when the indicating wheel 22 will show "Two" with 5.55 beneath it, or two times 5.55, which is 11.10. Multiples of these will continue until the divisions of the wheel 22 are exhausted. 105

The indicated savings will represent the amount that the depositor is temporarily saving up to be placed with the banker. 110

If the bank is to be used for any additional savings, coins of larger denominations may be inserted through the slot 6 but any coins passed through said slot will not be indicated on the dials or wheels, nor will any paper money passed through the opening 8. 115

By reference to Fig. 2 it will be observed that the mechanism containing case is supported against longitudinal movement with respect to the housing 1 by engagement of the grooved and slotted portions with the ribs 12. 120

A lock plate or floor plate 35 is provided with lugs 36, which engage openings 37 in the lower right hand corner of the case and the opposite edge of the plate is provided with a lock bolt 38, which engages in the notch 39 in the back of the housing 1, the bolt being part of the lock 40 and 125

adapted to be manipulated by a key 41, which will ordinarily be in the possession of the banker or trust company at which the deposit is to be made.

5 When the mechanism case is in place and the floor plate 35 is locked, any liability of the mechanism case becoming displaced or detached will be eliminated.

For convenience I may cover the openings 10 9, 10 and 11 with a glass panel or strip 42, which can be conveniently supported in the recessed portions 43 and 44 of the gear case which supports the wheels and ratchets.

It will be observed that by unlocking the 15 plate 35 and removing it, the mechanism case can be slid sidewise on the guide ribs 12 and then removed from the housing 1 through the opening closed by the plate 35, and since the front of the case is open, 20 access to the mechanism can be readily had for inspection or repairs without requiring the release or removal of bolts, nuts, screws or similar fastening devices.

What I claim and desire to secure by 25 Letters Patent is:

1. A bank comprising a housing having coin slots and windows therein, a registering mechanism case within the housing and having an open face adjacent to the windows, a transverse bar secured to the case, upstanding flexible strips carried by the bar and fulcrumed against the edge of the case,

depending pawls carried by the upper ends of the strips, the upper ends of the strips terminating above the bottoms of the coin 35 slots, wheels within the case, ratchets on the wheels for engagement with the pawls, a transverse bar in front of the wheels having pawls for engagement with the ratchets to prevent retrograde movement thereof, and 40 means for removably securing the case within the housing.

2. A bank comprising a housing, a removable case in the housing, supporting guides within the housing for engaging the 45 sides of the case, a shaft mounted in the ends of the case, ratchet wheels rotatable on the shaft, indicator wheels rigid with the ratchet wheels and having their perimeters adjacent to the windows, a bar near 50 the upper portion of the case, upstanding flexible strips, each having one end fastened to the bar and the intermediate portions bearing against the upper edge of the case whereby the upper edge of the case constitutes a fulcrum for said strips, and depending pawls carried by the upper ends of the strips and mounted for engagement with the ratchet wheels, the upper ends of the 55 flexible strips overlapping the lower ends 60 of the slots.

In testimony whereof I affix my signature.

PAUL A. HOLMES.
